(57) **CLAIM**

The ornamental design for a light for a vehicle, as shown and described.

DESCRIPTION

FIG. 1 is a perspective view of a light for a vehicle showing my new design.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is a bottom view thereof.

The broken lines in the drawings show a portion of a light for a vehicle that form no part of the claimed design. The broken line consisting of dot-dash lines is a boundary line that defines the bounds of the claimed design.
